(57) CLAIM

The ornamental design for an exercise equipment, as shown and described.

DESCRIPTION

FIG. 1 is a top plan view of my new design for an exercise equipment in a folded state;

FIG. 2 is a side elevation view thereof;

FIG. 3 is the other side elevation thereof;

FIG. 4 is a front elevation view thereof;

FIG. 5 is a bottom plan view thereof;

FIG. 6 is a perspective view thereof;

FIG. 7 is a perspective view of the inner side of the exercise equipment in an unfurled state;

FIG. 8 is a rear elevation view of the exercise equipment in a folded state;

FIG. 9 is another perspective view of the inner side of the exercise equipment in an unfurled state; and,

FIG. 10 is a perspective view of the outer side of the exercise equipment in an unfurled state.

The dashed broken lines illustrate portions of the exercise equipment that form no part of the claimed design. The jagged broken lines shown in FIGS. 6, 7, and 9 are for the purposes of illustrating portions of the inner side of the exercise equipment that form no part of the claimed design.
